ESCUTCHEON PLATE FOR AN IRON

Walter R. B. Hall, Somerville, N.J., and Walton E. Sparks, Lexington, Ohio, assignors to Westinghouse Electric Corporation, a corporation of Pennsylvania

Filed Nov. 27, 1968, Ser. No. 14,701

Term of patent 14 years

Int. Cl. D7—06

U.S. Cl. D49—6

FIG. 1

FIG. 2

FIG. 4

FIG. 3

FIG. 5

FIG. 1 is a perspective view of an iron disclosed for illustration purposes only and having an escutcheon plate of our new design;

FIG. 2 is a top plan view of an escutcheon plate incorporated in the iron shown in FIG. 1;

FIG. 3 is a rear elevational view of the escutcheon plate shown in FIG. 2;

FIG. 4 is a front elevational view of the escutcheon plate shown in FIG. 2; and

FIG. 5 is a side elevational view of the escutcheon plate shown in FIG. 2.

The dominant features of our design are shown in full lines.

We claim:

The ornamental design for an escutcheon plate for an iron, as shown and described.
